Primary Examiner — Ian Simmons*Assistant Examiner* — Dana L Meyrow(74) *Attorney, Agent, or Firm* — Mark J. Nahsen; Barnes & Thornburg LLP(57) **CLAIM**

The ornamental design for a bottle with cap, as shown and described.

DESCRIPTION

FIG. 1 is a top, front, right side perspective view of a bottle with cap showing my new design;

FIG. 2 is a bottom, rear, right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings illustrate the portions of the design that form no part of the claim.
